ABSTRACT

The present invention relates to improvements in double action cylinder or circular locks, which are applicable to doors and similar structures. The invention utilizes a single unitary construction forming the whole complex of doorknobs, casing, support and principal body in a single assembly. The mechanism makes it possible to act as a latch and/or a sliding bolt. The outer doorknob is fitted on a brass bar of suitable proportions, which in turn is inserted in the principal body the bar protecting the lock against violent lateral shocks.

IMPROVEMENTS IN DOUBLE ACTION CYLINDER OR CIRCULAR LOCKS, APPLICABLE TO DOORS AND SIMILAR OBJECTS

BACKGROUND OF THE INVENTION

1. Field of the Invention

The present invention is concerned with improvements in double action cylinder or circular locks, applicable to doors and similar objects.

2. Description of the Prior Art

The characteristics, variants and advantages of the invention will be appreciated from the description that follows, which refers to a form of embodiment with a double purpose, i.e., a latch and a dead bolt lock. In a preferred embodiment, the whole complex of door knobs, casings, supports, principal bodies and mechanisms forms a single unitary structural assembly.

For installation of the invention in doors, it is unnecessary to dismantle any of the component pieces, thus achieving great rapidity in their installation. In prior art case of the locks already existing on the market, they have to be separated into at least three parts in order to install them; this leads to a longer delay and a lesser perfection in the union of the different pieces, and requires more labor.

SUMMARY OF THE INVENTION

Among the characteristics presented by the present invention, possibly one of the principal advantages is that in the very limited space that cylinder locks occupy there is assembled a mechanism that can provide two functions with complete security: it functions as a thumb latch or slip bolt and as a sliding dead bolt.

Up to the present, in order to achieve security in doors, rim locks have been installed by making mortises in the wood, with the resultant weakening of the door and slowness of installation. Others, in accordance with the international standards of drill holes in doors, if it is desired to obtain security, have to install two locks, one of which fulfills the function of a latch and the other lock only having the mission of a sliding bar or dead bolt; consequently, in order to operate the two locks, two keys are required, one for each lock.

The present invention provides both a latch and dead bolt action in a single unit requiring only a single key.

Another advantage offered by the invention is its low cost of manufacture. Since it is concerned with double action cylinder locks, the most outstanding feature is the following: in the door in which the lock is to be fitted, a frontal drill hole is made in order to introduce the body and door knobs with their mechanisms completely assembled; another drill hole is made in the edge of the door, communicating with the first drill hole in order to introduce the casing of the bolt. Both parts are fixed with a single screw, and in order to make the assembly compact both parts are joined by means of an anti-shock cotter; in this way, complete security is achieved, preventing the lock from being forced from the outside. The exterior door knob is fitted on a brass bar of suitable dimensions which, in turn, is introduced into the main body, which bar prevents violent lateral blows to the interior of the assembly.

All the springs of the double action cylinder locks operate by compression.

BRIEF DESCRIPTION OF THE DRAWINGS

In this description, reference is made to the annexed drawings, in which:

5 FIG. 1 shows a perspective view of double action cylinder lock according to the invention with inner and outer doorknobs, the outer doorknob having a key slot.

FIG. 2 shows a perspective view second embodiment of the invention without an outer doorknob.

10 FIG. 3 shows a partial cross-sectional view of the doorknob assembly of the embodiment of FIG. 1.

FIG. 4 shows a cross-sectional view of the internal workings of the doorknob assembly of the embodiment of FIG. 1.

15 FIG. 5 shows a cross-sectional view taken along the lines V—V of FIG. 4.

FIG. 6 shows a cross-sectional view taken along the lines VI—VI of FIG. 4.

FIG. 7 shows a cross-sectional view taken along the 20 lines VII—VII of FIG. 4.

FIG. 8 shows a partial cross-sectional view of the invention taken along the longitudinal axis of the bar casting.

FIG. 9 shows the support sleeve for the outer doorknob.

FIG. 10 shows a partial cross-sectional view of the doorknob assembly of the embodiment of FIG. 2.

FIG. 11 shows a partial cross-sectional view of the doorknob assembly of the embodiment of FIG. 2.

30 FIG. 12 shows a cross-sectional view taken along the lines XII—XII of FIG. 11.

FIG. 13 shows a cross-sectional view taken along the lines XIII—XIII of FIG. 11.

FIG. 14 shows a cross-sectional view taken along the 35 lines XIV—XIV of FIG. 11.

FIG. 15 shows a perspective view of the bar casing.

FIG. 16 shows a perspective schematic view of the bar and its positional relationship with the front plate of the bar casing.

DESCRIPTION OF THE PREFERRED EMBODIMENTS

FIG. 1 shows a double action cylinder lock with inner and outer doorknobs, the outer doorknob having a key slot. The embodiment functions as both a latch and bolt.

FIG. 2 shows double action cylinder locks with an inner doorknob and outer key, a practical variation of the embodiment of FIG. 1.

50 FIG. 3 shows the double action cylinder lock cut away at its doorknobs (36) and (37), the cut-away casing (35) showing the support for the inner doorknob (15), the principal body (17), the key-groove (27) for the bolt casing (22), orifice (28) for the engaging of the connecting rod (19), and support for the outer door-knob (30).

55 FIG. 4 shows in its sectioned form the inner door-knob support (15), the sliding bolt (4), the inner knob spring (6), the checkpiece (16) of the doorknob (36), which checkpiece enters into play when the doorknob (36) is pulled outwards, the eccentric piece (8) fixed with the screw (10), which is designed so that when it is well tightened the eccentric piece turns freely.

60 Likewise, in FIG. 4, details are shown of the principal body (17) on which the shank (31) acts, the sleeve (12) in which the key cylinder (11) is fitted, the key cylinder (11) the bushing 18, the key (14), the combi-

nation (13), the cotter (5) fixed to the key cylinder (11) whose mission is that of moving the sliding bolt (4) when the lock operates with the key. The cutter (5) is also the checkpiece for the latch when the two door-knobs function in combination with the sliding bolt in the latch mode of operation.

In the three sections that are taken in FIG. 4, details are shown of the following pieces: FIG. 5 (section through V—V of FIG. 4): sliding bolt (4), passageway (34) for the travel of the inner doorknob, spring (3) of the thumb latch, recess (33) where the spring (3) is situated. FIG. 6: (section through VI—VI of FIG. 4): sliding bolt (4), the eccentric piece (8) with its recess for shank (31) rotatable by the outer doorknob (37), coupling bolt (7) which is joined to the connecting rod (19) which moves the bar (2), the screw (10) for fixing the eccentric piece. FIG. 7 (section through VII—VII of FIG. 4): sliding bolt (4), coupling bolt (7), cotter (5) fixed to the cylinder (11) by a pin, shank (31) of the outer doorknob support, slot (32) for the travel of the latter.

FIG. 8 shows the whole of the mechanism that moves the bar: the bar (2), the casing (22) for the bar the pivot pin (21) for connecting rod (19), the spring (20) for the connecting rod (19), the connecting rod (19), the coupling bolt (7) for the connecting rod (19), the sliding bolt (4) fixed to the support (15) of the inner doorknob, the eccentric piece (8), the screw (10) for fixing the latter.

FIG. 9 shows the support (30) of the outer doorknob (37) and the shank (31).

The assembly of all the elements, in the double action cylinder lock is effected in the following manner: there is introduced under pressure the sleeve (12) into the outer doorknob support (30); in the recess between the sleeve (12) and the doorknob (37) the shank (31) is also introduced under pressure. This complex of doorknob, sleeve and shank turns freely between the head of the sleeve (12) and the principal body (17): there is thus achieved the free rotation of the outer doorknob provided that it is not locked with a key, as will be explained later.

FIG. 2 shows the double action cylinder lock, in an alternative embodiment of the invention, showing an inner doorknob and outer key. FIGS. 10 and 11, and the sections shown in FIGS. 12, 13 and 14 taken, along the axes XII—XII, XIII—XIII and XIV—XIV of FIG. 7, represent the components and situation of the pieces that form the double action cylinder lock, in accordance with this embodiment. Since they are pieces common to the double action cylinder lock detailed in FIG. 1, and designated by the same numbers, they are not repeated in this paragraph. The only element that varies is the eccentric piece (9) there being eliminated in this embodiment the outer doorknob (37) and the shank (31).

By reference to FIG. 15, there may be appreciated the function of the bar (2) with its different components: case shield plate (23), bar case (22), drill hole (24), to introduce the fixing screw for fixing the case, bar, and doorknob assembly, space (25), for housing the bar (2) guide and anti-shock cotter (26).

FIG. 16 shows the complex of the bar and the connecting rod. There can be seen in this Figure the emergence of the bar (2) in a normal latch position (position 1) where rotation of either inner or outer doorknob (or key) will retract bar (2) substantially into the bar case

(22). FIG. 16 also shows the extended position (position 2) of bar (2) where the bar (2) acts as a dead bolt. Functioning of the double action cylinder lock (inner doorknob action).

Taking as an example the embodiment shown in FIG. 1: by means of turning the doorknob (36) through a first sector the latch is concealed in the case (22) that supports it in order to leave the door free; in the first sector, sliding bolt (4) is free to rotate unrestricted by cotter (5); the bar (2) is urged outwardly to position 1 (FIG. 16) by the spring (3) which acts against the bolt (4) fixed to the support (15) of the doorknob (36). On releasing the doorknob, the spring (3) returns the doorknob (36) and bar (2) to their original position, (position 1) of FIG. 16.

In order to effectuate dead bolt action of the bar, the doorknob (36) is pulled slightly outwards and turned through a second sector extending beyond the limits of the first sector and in a direction opposite to the direction the doorknob (36) is turned to retract bar (2) within case (20). The operation of pulling out is effected so that the sliding bolt (4) will pass above (axially to the left in FIG. 4) the fixed cotter (5) when it is operated by the interior of the double action cylinder lock. In this position, the cotter (5) prevents movement of the sliding bolt (4) by rotation of the outer doorknob (37). On releasing the doorknob, the latter returns to its former position as a result of the action of the force of the return spring (6) which was tensed at the moment of pulling out the doorknob; in order to draw back the bar, the same operation is carried out in inverse order.

Function of the double action cylinder lock, (outer doorknob action).

Provided that the inner doorknob has not shot the bar along its maximum security movement (position 2 of FIG. 16), the latch can be concealed in the case (22) that supports it by effecting corresponding rotation of the doorknob (37), leaving the door free. This operation can be effected since the doorknob is linked by means of the shank (31) with the eccentric piece (8) which is joined to the connecting rod (19) of the bar.

If it is desired to shoot the bar from the outside, this can only be done with the key. There is brought into play the key cylinder (11) which, with its cotter (5) moves the sliding bolt (4) which, in turn, moves the eccentric piece (8) to the position shown in FIG. 8. In this way, the bar travels to its maximum extent, leaving the door where the lock is fixed in a situation of complete security.

Without using the key (14) to operate the outer doorknob, the latter remains blocked and cannot be moved. It is only the key (14) that can move cotter (5) out of the path of sliding bolt (4) permitting the bar (2) to travel in order to leave the doorknob free; but once the key has been turned, one can open the lock from the inside in the manner explained with respect to the functioning of the inner doorknob.

The functioning of the double action cylinder lock, as is shown in FIG. 2, with its inner doorknob, is identical with that of the cylinder lock shown in FIG. 1, and from the outside, using the key, the same operation serves for shooting and withdrawing the bar and for withdrawing the latch.

Assembly of the lock in the door.

This is done in the following manner: once the orifices have been made in the wood, there are introduced the casing, doorknob and the whole of the doorknob assembly, without dismantling any of the elements, until the assembly is centered in the door and an opening in the side of casing (35) is aligned with the orifice drilled in the door edge. The bar is set to its closed position. The casing of the bar is then introduced through the orifice on the edge of the door until the cotter (26) of the casing is introduced into the key groove (27) of the body of the lock; thereafter, both parts are secured with the fixing screw. Finally, slight pressure is applied to the bar so that the connecting rod will begin to slide, compressing the spring (20) against bar case (22) until connecting rod (19) engages the bolt (7); the connecting rod rises because constant pressure continues to be applied until finally, on reaching the maximum degree of introduction, and because the spring (20) is being tensed, the connecting rod definitively engages with the coupling bolt (7); in this way, the bar, connecting rod and bolt are joined. The lock is now fitted for functioning. The operation of assembly is carried out in a maximum time of twenty seconds.

If for any reason it is necessary to remove the lock from the door, this is done in the following manner: the bar is situated in the closed position; the fixing screw is then withdrawn, and subsequently the casing (22) of the bar is withdrawn until the cotter (26) emerges from the key groove (27); the lock (doorknob and casing) is then displaced towards the interior of the room, until the connecting rod (19) is freed from the bolt (7), which is shorter than the width of the orifice (28); finally, on the connecting rod remaining free, there is effected the total extraction of the block formed by the casing of the bar, the bar and the connecting rod. This operation of dismantling is carried out in a maximum time of fifteen seconds.

All that has been expounded constitutes a faithful reflection of the invention; it should be considered in a broad sense, and never in a limitative form, the conditions in which the invention is embodied being variable with respect to the sizes, forms, proportions and materials employed, provided that there are not altered or modified the fundamental characteristics that typify it, the inventor reserving to himself the right to protect the improvements that may be introduced into the object of the invention, or that practice makes it advisable to carry out.

What is claimed is:

1. In a double action cylinder lock of the type applicable to doors and similar structures, said lock having at least one doorknob, a doorknob actuator assembly, and a bar slideable in a casing, and wherein said doorknob actuator assembly is fitted for insertion into an opening in the plane of the door or similar structure and said bar and bar casing are fitted for insertion into an orifice through the edge of the door or similar structure, said orifice meeting with and oriented normal to said opening, the improvement in which:

said doorknob and doorknob actuator assembly form a unitary structure;

said doorknob is sized to fit through said opening without disassembly from said unitary structure;

40

45

50

55

60

65

and

said doorknob actuator assembly comprises means for fixedly receiving the inner end of said bar casing, and means for coupling said doorknob actuator assembly to said bar.

5 2. The improvement of claim 1, wherein said means for receiving is a threaded aperture into which a fixing screw from said bar casing is secured.

10 3. The improvement of claim 2, wherein said means for receiving includes a slot and said bar casing includes a guide member projecting from the inner end of said bar casing, the guide serving to align said bar casing with said doorknob actuator assembly and to prevent axial movement of said doorknob actuator assembly.

15 4. The improvement of claim 1, wherein said bar includes a connecting rod with a hooked end, and said doorknob actuator assembly includes a coupling bolt rotatable with said doorknob and about which said hooked end is coupled, said bar casing including a spring for biasing said connecting rod in a direction to couple said hooked end about said coupling bolt.

20 5. The improvement of claim 8, wherein:

25 said doorknob actuator assembly includes means for drawing said bar into said casing; said coupling bolt is fixed to a support plate rotatably mounted in said doorknob actuator assembly; and said doorknob actuator assembly includes blocking means positionable to block rotation of said plate and thereby selectively prevent and permit withdrawal of said bar into said casing.

30 6. The improvement of claim 4, wherein said doorknob is an inner doorknob, and including:

35 a projection extending from the inner doorknob toward the center of said doorknob actuator assembly and rotatable with said inner doorknob; a key cylinder subassembly having a stop means fixed at the end thereof and in the path of said projection, said stop means limiting the extent of movement of said projection in one direction of movement at which point said bar is in a latch position with said bar extending out of said casing; a resilient means urging said projection in said one direction, said resilient means being compressed by said projection when said inner doorknob is rotated to move said projection in a direction opposite said one direction; and

40 means to move said projection beyond said stop means thereby moving said bar to a dead bolt position beyond said first position, at which dead bolt position only the inner doorknob or key subassembly is effective to move said projection back to the latch position.

45 7. The improvement of claim 6, wherein said means to move said projection comprises a shaft along which said inner doorknob is slideable; and a compression spring urging said inner doorknob toward said doorknob actuator assembly; whereby pulling on said inner doorknob permits the free end of said projection to pass by said stop means.

50 8. The improvement of claim 6, wherein said key subassembly is effective to move said projection to position said bar at said second position.
